PATENTED MAR. 3, 1908.

F. J. MELTON.
HEATING SYSTEM.

APPLICATION FILED APR. 6, 1907.

UNITED STATES PATENT OFFICE.

FRANK J. MELTON, OF CHICAGO, ILLINOIS.

HEATING SYSTEM.

No. 880,806.

Specification of Letters Patent.

Patented March 3, 1908.

Application filed April 6, 1907. Serial No. 366,793.

To all whom it may concern:

Be it known that I, FRANK J. MELTON, citizen of the United States, residing at Chicago, in the county of Cook and State of Illinois, have invented certain new and useful Improvements in Heating Systems, of which the following is a specification.

This invention relates to heating systems, and has for its object to provide means whereby buildings or other structures may be heated with greater economy, and in a more efficient manner, than hitherto.

The system includes steam heating appliances, with which are associated air heating appliances, the steam and hot air being transmitted through the same pipes to the radiators.

The ordinary boiler is provided with a series of air pipes located in the steam space 20 of the boiler and also in the breeching and smoke stack, and these pipes are connected on one side to the main steam supply pipe, and on the other side to an air tank and compressor, the heated air being supplied under 25 pressure and forced through the coils and thence into the steam pipes and to the radiators in which it circulates with the steam, the air being at the same temperature as the steam.

30 The steam and air are both in the pipes of the system at the same time, and after condensation of the steam the water is returned to the boilers by the pumps in the usual manner and the air escapes through a relief 35 valve in the return pipes.

The air and steam pipes may be provided with reducing valves so controlled that the proportions of steam and air to be used may be controlled by the engineer.

40 The air coils are so associated with the steam boilers that the large amount of heat which escapes from the ordinary steam boiler or furnace is utilized to heat the air, whereby a great economy of operation is attained.

45 An embodiment of the invention is illustrated in the accompanying drawings, in which

Figure 1 is a sectional view of a part of a building to which the system is applied, the 50 parts of the system being shown in elevation. Fig. 2 is a detail in section.

Referring specifically to the drawings, the boilers are indicated at 6, of tubular or other suitable construction, and these are connected to the main heating or steam pipe 7, through which steam is supplied, to the

radiators 9 by means of branch feed pipes 8. The return pipe is indicated at 10, leading to the water pump 11, which is connected to the boilers by pipe 40, by which water is returned 60 to the boilers. This forms an ordinary steam heating system.

The boilers are provided with air heating coils or pipes. These may be conveniently disposed to utilize the spare heat of the 65 furnace. Thus I show the pipes at 12, located in the furnace and connected back and forth to give a large heating area or space; also located in the breeching, as at 13, and in the steam space of the boilers as indicated at 15. These coils and pipes are all connected together to allow a circulation of air therethrough, the inlet pipe from the air tank being indicated at 16, on one side, and the outlet pipe indicated at 17, leading to the 70 main supply pipe 7. The air is preferably led directly from the coils inside the boiler, to the supply pipe, so that the air will be the same temperature as the steam.

The air is supplied through the pipe 16 80 from a tank 18 which is supplied through a pipe 19 from the air compressor or pump 20 which is operated by steam admitted through a pipe 21 connected by branch pipes 22 to the main steam pipe 7 and the air pipe 16. 85 These branch pipes are provided with equalizing valves 23. The return pipe 10 has an air relief valve 24 which allows the escape of the cold air returning through the pipe, the water passing on to the pump. 90

In operation, the air under pressure is supplied through the pipe 16 and passes through various coils above or around the furnace and is thereby heated to practically the same temperature as the steam, and passes thence 95 with the steam to the radiators where it performs its useful function. The relative amounts of steam and air can be controlled by the use of valves in the different pipes, and in consequence of the location of the air tubes, as described, a comparatively large body of air is exposed to the products of combustion, in the boiler setting, the breeching, and the stack, thereby saving the heat which would otherwise be wasted. Of course the 105 steam system can be used without air if so desired, but the latter will be found to be an efficient aid for heating purposes, and to economize fuel, since the air may be supplied even while the boilers are not making steam. 110 The equalizing valves 23 are checked against each other so that if the air pressure

is the stronger it will close or cut off the steam until the pressures are equalized, or if the steam pressure is the stronger it will close the air and operate the compressor 5 until the pressures are equalized.

I claim:

1. In a combined steam and air heating system, the combination with a boiler, and a main steam pipe leading therefrom, of an air 10 compressor having a pipe connection extending through the boiler and to the said steam pipe, a pipe for motive power, connected to the compressor and having branches connected to said air and steam pipes, and check 15 valves which open toward each other in said branches.
2. In a combined steam and air heating system, the combination with a boiler and

its furnace, and a supply pipe leading from the boiler, of an air pump, an air pipe leading therefrom to the said supply pipe and exposed intermediately to the heat of the furnace, a branch pipe from the said supply pipe to the pump, to supply pressure to operate the latter, and a branch pipe connecting said last mentioned pipe and the air pipe, each of the branch pipes having a check valve therein which opens toward the other, to stop the pump when the air pressure equals the steam pressure. 20 25 30

In testimony whereof I affix my signature, in presence of two witnesses.

FRANK J. MELTON.
